J. NEEDHAM.

GAS MIXER.

APPLICATION FILED JAN. 8, 1921.

1,411,062.

Patented Mar. 28, 1922.

FIG. 1.

FIG. 2.

FIG. 3.

Inventor
Joseph Needham
By his Attorneys

Edgar Walter S.

UNITED STATES PATENT OFFICE.

JOSEPH NEEDHAM, OF PASSAIC, NEW JERSEY.

GAS MIXER.

1,411,062.

Specification of Letters Patent. Patented Mar. 28, 1922.

Application filed January 8, 1921. Serial No. 435,824.

To all whom it may concern:

Be it known that I, JOSEPH NEEDHAM, a subject of the King of Great Britain, and residing at Passaic, in the county of Passaic 5 and State of New Jersey, have invented certain new and useful Improvements in Gas Mixers, of which the following is a specification, such as will enable those skilled in the art to which it appertains to make and 10 use the same.

This invention relates to gas mixers and particularly to devices of this class for use in connection with fuel gas burners, and the object of the invention is to provide a device 15 of the class specified with a high pressure adjustable fuel discharge nozzle whereby the relative position thereof to the throat of the mixing device will control the entrainment of air thereinto thus obtaining the desired and most efficient combustible mixture; and with this and other objects in view the invention consists in a device of the 20 class specified which is simple in construction and operation, and which is constructed 25 as hereinafter described and claimed.

The invention described and claimed herein is an improvement on that described and claimed in a prior patent granted to me October 19, 1920, No. 1,355,998, and is fully 30 disclosed in the following specification, of which the accompanying drawing forms a part, in which the separate parts of my improvement are designated by suitable reference characters in each of the views, and 35 in which:—

Fig. 1 is a plan view of my improved mixing device;

Fig. 2 a section on the line 2—2 of Fig. 1; and,

Fig. 3 a view similar to Fig. 2 with part 0 of the construction shown in said figure in full lines and showing a modification.

In Figs. 1 and 2 of the drawing, I have indicated at 5 the main body portion of my 5 improved device and at 6 a supplemental tubular body portion. The main body portion 5 is provided at one end with a ring member 7 formed integral with said body portion through arms 8, which form a large aperture 9 in the main body portion through which air is adapted to pass into the supplemental body portion.

The supplemental body portion is provided with an enlarged head 10 adapted to receive the ring member 7 and to which said head is secured by screws or bolts 11, as

clearly shown in Fig. 2. The head end of the supplemental body portion is provided with a reduced throat 12 which flares outwardly into the aperture 9, as shown at 13, 60 and the supplemental body portion is provided outwardly of the throat 12 with a tapered or flaring mixing chamber 14. The free end portion of said supplemental body portion is preferably threaded as indicated 65 at 15 to permit of its connection with a furnace or similar apparatus.

The main body portion 5 is provided with a fuel chamber 16 and fuel is adapted to be admitted into said chamber through an 70 aperture 17. A tube 18 is adjustably mounted in the main body portion 5 and communicates with the chamber 16 and extends outwardly through one end of said body portion into the aperture 9, and the outer 75 end of said tube is provided with a detachable nozzle 19. The tube 18 and nozzle 19 form an adjustable fuel discharge device which is movable toward and from the throat 12 of the supplemental body portion 80 to control the entrainment of air into the mixing chamber 14 of said body portion in the passage of fuel thereinto through the nozzle 19.

The adjustment of the tube 18 may be 85 accomplished in many ways, but in the construction shown a hexagon end 20 is provided on said tube and in order to prevent the leaking of fuel or fuel gas from the fuel chamber 16 outwardly around the tube 18, a 90 suitable packing ring 21 is employed, which is held in place by an adjustable sleeve 22.

It will be seen from the foregoing description that the fuel gas employed which is usually under a predetermined pressure is 95 passed into the chamber 16 of the main body portion and thus out through the tube 18 and nozzle 19 into the mixing chamber 14 of the supplemental body portion, and the position of the nozzle 19 relatively to the 100 throat 12 will control the entrainment of air through the throat and into the mixing chamber 14 thus regulating the mixture of fuel and air passed into said mixing chamber and thus into a furnace or similar apparatus. With the construction shown it 105 will be apparent that the adjustment of the tube 18 and nozzle 19 may be readily performed, whenever desired or necessary, and it will also be seen that the air drawn into 110 the mixing chamber 14 will not be obstructed, or the flow thereof retarded in any

way thus producing a very effective and efficient gas mixing device of the class and for the purpose specified.

In the construction shown in Fig. 3 of the drawing I have shown a slight modification in which the supplemental body portion 6 is provided at its inner or head portion with a tubular member 23 which is adjustably mounted in said body portion, said tubular member being provided with the reduced throat 12 which flares outwardly, as shown at 13, and the mixing chamber 14 will be formed partially in the tubular member 23 and the supplemental body portion 6. The adjustment of said tubular member may be accomplished through the aperture 9 by a spanner wrench or the like engaging apertures 24 in the periphery of the protruding portion of said tubular member.

With the construction shown in Fig. 3 of the drawing by reason of the adjustable as well as the detachable tubular member 23, the relative size of the throat 12 may be varied by the use of tubular members of different sizes, and the position of said throat in the supplemental body portion may also be varied. It will also be noted that with the construction shown in Fig. 3 the admission of air through the aperture 9 into the mixing chamber may be materially shut off or choked by adjusting the tubular member 23 outwardly into the aperture 9 with the sleeve 18 and nozzle 19 in their innermost position as shown in Fig. 2 of the drawing.

It will be apparent that while I have shown certain details of construction for carrying my invention into effect, I am not necessarily limited to these details, and various changes therein and modifications thereon may be made, within the scope of the appended claims, without departing from the spirit of my invention or sacrificing its advantages.

Having fully described my invention, what I claim as new and desire to secure by Letters Patent, is:—

1. A gas mixing device of the class described comprising a main body portion provided with a fuel chamber, means for admitting fuel into said chamber, a ring member at one end of the body portion joined therewith by arms, and a supplemental body portion detachably mounted in connection with said ring member and provided with a mixing chamber having a reduced and outwardly flaring throat, and a fuel discharge tube adjustably mounted in the main body portion and provided with a discharge nozzle movable toward and from said throat to control the entrainment of air into the mixing chamber through said throat.

2. A device of the class described com-

prising a main body portion provided with a fuel chamber, a supplemental tubular body portion detachably connected with the main body portion and provided with a flared throat, inwardly of which is a mixing chamber, means whereby fuel may be admitted into the fuel chamber, and a fuel discharge device adjustably mounted in the main body portion and communicating with the fuel chamber thereof and movable toward and from said throat.

3. A device of the class described comprising a main body portion provided with a fuel chamber, a supplemental tubular body portion detachably connected with the main body portion and provided with a flared throat, inwardly of which is a mixing chamber, means whereby fuel may be admitted into the fuel chamber, a fuel discharge device adjustably mounted in the main body portion and communicating with the fuel chamber thereof and movable toward and from said throat, and means whereby air may pass through the main body portion and into the supplemental body portion through said throat and around said fuel supply device.

4. A device of the class described comprising main and supplemental body portions, said main body portion being cut out to form an air space, said supplemental body portion being tubular in form and provided with a mixing chamber opening outwardly through one end thereof, a tube adjustably and detachably mounted in the other end thereof and provided with an outwardly flaring throat which communicates with said air space, the main body portion being provided with a fuel chamber and a fuel discharge device adjustably mounted in said main body portion and movable toward and from the throat of said tube to control the entrainment of air into said mixing chamber.

5. A gas mixing device of the class described comprising a suitable body portion composed of separate parts having an air space therebetween, a tubular member adjustably mounted in one of said parts and provided with an outwardly flaring throat inwardly of which is a mixing chamber, and a fuel discharge device adjustably mounted in the other of said parts and movable toward and from the throat of said tubular member.

In testimony that I claim the foregoing as my invention I have signed my name in presence of the subscribing witnesses this 5th day of January, 1921.

JOSEPH NEEDHAM.
